VENTILATING UNIT

Herbert D. Euwer, Kirkwood, Mo., assignor to
American Car and Foundry Company, New
York, N. Y., a corporation of New Jersey

Application December 30, 1947, Serial No. 794,681

3 Claims. (Cl. 98—19)

1

This invention relates to ventilating units in general and in particular to ventilating units having forced discharge and intended for railway passenger car use.

Railway passenger cars have for years been ventilated by means of an eduction type ventilator, that is, one where the movement of the car caused the air to be drawn out of the vehicle. Recently with the use of certain air conditioning units, the entire car interior has been placed under pressure and this pressure assisted the ventilation through the eduction type fixture. Such fixtures have not given a definite and predictable ventilation of the cars. It is an object, therefore, of the present invention to provide a forced ventilation for a railway car which does not rely on either internal or external car pressures for its operation.

A further object of the invention is the provision of a ventilating unit which can be readily installed and serviced.

A still further object of the invention is the provision of a ventilating unit having a discharge grille closely conforming to the contour of the car roof.

A yet further object of the invention is the provision of a ventilating unit having a fan swingable between a vertical in-use-position and a horizontal inspection or repair-position.

These and other objects of the invention will be apparent to persons skilled in the art from a study of the following description and accompanying drawings, in which

Figs. 1 and 1A, when taken together, disclose a complete sectional view of the unit taken substantially on line 1—1 of Fig. 2;

Fig. 2 is a sectional view taken substantially on line 2—2 of Fig. 1;

Fig. 3 is an elevational view of the discharge grille with parts removed to better disclose the construction;

Fig. 4 is a sectional view taken substantially on line 4—4 of Fig. 1;

Fig. 5 is a sectional view taken substantially on line 5—5 of Fig. 1A, and

Fig. 6 is an enlarged sectional view taken substantially on line 6—6 of Fig. 1A.

Referring now to the drawings in detail it will be seen that the unit has been disclosed as applied to a passenger car having a curved roof 2 attached to carline 4 and purlines 6, the carlines and roof being attached to the side plate 8. The roof sheet 2 intermediate the carlines has an opening 10 cut therein and on the inner surface of the roof sheet is attached an open ended

box-like duct 12. The outer open end of this box-like duct is flanged and rigidly attached to the roof sheet, thereby reenforcing and stiffening the roof sheet at the opening and sealing the roof and box-like duct against passage of moisture of the car interior. Inwardly of the open end of the duct is fastened a pan-shaped plate 14 having an opening cut therein for reception of an eliminator frame 16 which is bolted or otherwise secured to plate 14 and which, together with the eliminator plates carried in the frame, can be removed through the open outer end of the ducts. The duct member has its inner end preferably supported from either the carlines or purlines by means of hangers 18 and the inner edge of the duct is flanged as at 20 so that plate 22 can be attached thereto. Plate 22 forms the outer open end of a fan housing 24, having the other open end directed downwardly toward the car interior. Rigidly attached to plate 22 is a hinge plate 26 by means of which a plate 28 can be hinged to the plate 22. The plate 28 as shown has integrally attached or pressed therein a flange 30 defining a circular opening for reception of fan blades 32, these fan blades being driven by a motor M attached to the plate 28. The plate 28 with the attached motor and fan is normally held in the vertical or operative position by a pair of releasable fasteners 34 which are adapted to grip plate 22.

The lower or downwardly directed open end of fan housing 24 is flanged inwardly to have attached thereto the inturned flanges of a filter housing member 36. The lower outturned flanges 38 of this filter housing member are adapted to support the ceiling sheets 40 and form a binding around the opening in the ceiling plate. The filter housing is adapted to receive a filter member 42 and a screen or inlet grille 44 hinged as at 46 to the filter housing and held in normal position by releasable fastening 48.

In order to permit discharge of air through the box-like duct and roof while preventing entrance of large particles of foreign matter, a discharge grille is provided as best shown in Figs. 1A and 3. This discharge grille is preferably formed as a unitary structure with a substantially rectangular frame 50 conforming to the roof's curvature and adapted to overlap the roof surrounding the opening cut therein. Extending outwardly from the rectangular frame is a pair of generally triangular shaped sides 52 located with the base uppermost and these sides are tilted toward each other and inclined upwardly and inwardly as best shown in Fig. 3. In other words, they are

inclined toward each other both longitudinally and transversely of the car. The upper or base ends of the sides merge into a top member 54 directed inwardly and upwardly to merge with the upper portion of the rectangular frame. The outer edges of triangular sides 52 and top 54 terminate in a plane substantially tangent with the roof at the lower edge of the opening. In other words, their outer surface lies substantially in the plane of the lower element 56 of the rectangular frame. The sides 52 are joined by horizontal bars 58 and the top 54 and bottom 56 are joined by a vertical bar 60, which also is made integral with bars 58. As clearly shown, the upper edge of the grille is connected to the car roof by hinge 62 preferably of the continuous type and capable of excluding practically all moisture coming in contact therewith. Any moisture that may enter the duct through the open grille work or along the sides of the grille can discharge out of the duct due to the slight spacing of the lower edge 56 from the roof as shown in Fig. 1A. The grille as shown in Fig. 6 is held in position against swinging by means of screw fasteners 64 fastened through the lower edge of the grille and into plates 66 fastened on the interior of duct 12.

The grille will, due to its close conformation to the car roof, enhance the appearance of the car while at the same time permitting efficient discharge of air from the car interior. The inclined sides 52 will assist in directing the flow of air around the grille so as not to hamper discharge of air through the grille. The eliminators in eliminator housing 16 will prevent entrance of moisture any distance into the duct under conditions when forced ventilation is not in use. If at any time it becomes necessary to repair or service the fan this can be readily done by dropping the filter and screen to the line and dash position of Fig. 1 and after unfastening fasteners 34 the fan assembly can be swung downwardly about hinge 26 to a substantially horizontal inspection or repair position.

While the invention has been described more or less in detail with specific reference to the drawings, it will be obvious to persons skilled in the art that various modifications and rearrangements of parts may be made and all such modifications and rearrangements are contemplated as will fall within the scope of the appended claims.

What is claimed is:

1. An exhaust ventilator for a railway passenger car having a curved roof with an opening cut therein for the passage of air through the roof, a member overlapping the opening and comprising an open, substantially rectangular base frame conforming to the roof curvature, sides of generally triangular form extending outwardly of the car from the base frame and inclined toward each other both longitudinally and transversely of the car, and a top connecting said sides and base frame and extending outwardly and downwardly from the upper edge of the base

65

frame, said top and sides terminating in a plane substantially tangent to the roof and lower edge of said base frame and defining an exhaust opening for the passage of air.

2. An exhaust ventilator for a railway passenger car having a curved roof with an opening cut therein for the passage of air through the roof, a member overlapping the opening and comprising an open, substantially rectangular base frame conforming to the roof curvature, sides of generally triangular form extending outwardly of the car from the base frame and inclined toward each other both longitudinally and transversely of the car, a top connecting said sides and base frame and extending outwardly and downwardly from the upper edge of the base frame, said top and sides terminating in a plane substantially tangent to the roof and lower edge of said base frame, and horizontal and vertical bars connecting said sides and top and defining therewith openings for the passage of air.

3. An exhaust ventilator for a railway passenger car having a curved roof with an opening cut therein for the passage of air through the roof, a member overlapping the opening and comprising an open, substantially rectangular base frame conforming to the roof curvature, sides of generally triangular form extending outwardly of the car from the base frame and inclined toward each other both longitudinally and transversely of the car, a top connecting said sides and base frame and extending outwardly and downwardly from the upper edge of the base frame, said top and sides terminating in a plane substantially tangent to the roof and lower edge of said base frame to define an exhaust opening, grille work in said opening and connected to said sides and top, and a hinge connecting the upper edge of said base frame and roof whereby said member may swing relative to said roof.
